TREATMENT OF HYDROCARBON OILS

Jacque C. Morrell, Chicago, Ill., assignor to
Universal Oil Products Company, Chicago, Ill.,
a corporation of Delaware

No Drawing. Application August 7, 1933,
Serial No. 684,126

4 Claims. (Cl. 196—30)

This invention refers more particularly to the treatment of the relatively low boiling gasoline-containing distillates produced as a result of the cracking of heavy hydrocarbon oil mixtures.

5 In a more specific sense the invention is concerned with a method of treatment which may be employed either by itself or in conjunction with other treating steps to produce from cracked distillates gasolines acceptable to the trade from 10 the standpoint of such properties as color, odor, gum content, sulphur content, et cetera. The process is particularly effective in sweetening and desulfurizing high sulfur cracked distillates, as will be developed later.

15 Difficulties in refining cracked distillates, particularly those produced from high sulfur charging oils, are quite generally known to petroleum refiners. Sulfuric acid of varying strength is the most generally employed treating reagent. However, it is not entirely specific in respect to its 20 action upon the different undesirable groups of compounds present, to-wit, diolefins (gum formers), corrosive and odorous sulfur compounds, et cetera. Thus, when sufficient sulfuric acid is utilized to insure the desulfurization of some 25 cracked naphthas, there is a concurrent removal of too much of the mono-olefins which contribute to the anti-knock value of the final product without adding to its gum-forming tendencies or decreasing its stability under normal conditions 30 of exposure to light and air. When using treating solutions according to the present process, the amount of sulfuric acid necessary can frequently be reduced to a minimum value so that less loss 35 is entailed.

Redistillation of the treated naphtha or gasoline is practically always necessary after even a mild sulfuric acid treatment owing to the formation of soluble sulfuric acid esters and of high boiling polymers, et cetera, and, in the case of relatively heavy treatments, the temperature employed in redistilling the treated product must be kept below a certain point to prevent decomposition of soluble sulfur compounds and the production of a sour overhead product.

45 In one specific embodiment the invention comprises treatment of gasoline-containing hydrocarbon distillates in liquid or vapor phase with aqueous solutions containing both mercury and copper salts, e. g. mercuric chloride and cupric chloride. Salts of mercury and copper are the most desirable from the viewpoint of their reactivity with sulphur compounds in petroleum.

50 The two salts mentioned are used together in treating cracked distillates with particular ad-

vantage for several reasons. In the first place, tests have shown that the mercury salt has a higher limited solubility in water in the presence of the copper salt than it has alone, which enables the employment of higher concentrations and consequently more intensive and selective treating action, along with other advantages which will be brought out more in detail in describing the method of application of such solutions. The following table shows the composition of 65 four mercuric chloride-cupric chloride solutions at the saturation point at ordinary temperatures and pressures:

Solution	Mercuric chloride—weight percent	Cupric chloride—weight percent	70
1	0	44.47	75
2	37.3	26	
3	52.6	18.5	
4	8.5	0	

The limit concentration of either salt will be determined by the amount of the other salt present, the table showing two solutions of maximum total concentration as Solutions 2 and 3. These concentrations may be varied in either direction to take advantage of the particular treating action of either salt upon different types of sulfur compounds and other undesirable groups such as, for example, diolefins. According to this concept the concentration of the treating solutions may be varied generally within the limit solubilities of either salt, though obviously each specially prepared solution will exert its own particular treating action which will depend not only upon its concentration and the relative proportion of the two salts, but also upon the conditions under which they are applied such as the presence of liquid, mixed or vapor phase, temperature, pressure, efficiency of contact, et cetera. Accordingly, the various alternatives are not to be considered as exact equivalents in their action upon the same or upon different cracked distillates.

100 The actions of mercuric chloride and cupric chloride, respectively, upon the various types of sulfur compounds in petroleum and upon unsaturated hydrocarbons of a diolefinic character, which occur in varying percentages in cracked distillates from different sources differ somewhat. The mercury salt is active in combining directly with mercaptans which account principally for the sour character and bad odor of low boiling cracked products, the products of this reaction 110

being direct molecular addition compounds, frequently of a semi-crystalline character, which are quite insoluble in the oil. The mercury salt also reacts with olefins, particularly those of a diolefinic character, and by choosing the proper concentration of the composite solution and selecting the conditions of operation it is possible to remove both a sufficient amount of sulfur and the major portion of the gum-forming olefins 10 without recourse to sulfuric acid. Copper salts as a compound of the treating reagent also have a distinctive action.

The present type of treating solutions may be applied to cracked distillates in liquid or vapor 15 phase and at any desired stage in the refining operations thereon, including their use upon the rerun end point product. Liquid phase treatments may be conducted in the same type of equipment usually employed for sulfuric acid 20 treatment, to-wit, the ordinary batch agitator or the continuous treating plant consisting of alternate mixing and settling units. These types of operation are well known in the industry and need no detailed description.

25 In treating vapors such as those arising from the fractionators of cracking units or from the rerun stills, several modes of operation are possible. The solutions may be injected into a stream of vapors prior to their entering a fractionating column and the spent reagents and the products of the reaction allowed to settle in an intermediate chamber preceding the fractionator. In other cases vapors may be passed upwardly 30 through filled towers counter-current to descending streams of treating solutions, after which treated vapors are finally fractionated. To maintain the concentration of the treating solutions under the temperature conditions encountered in vapor phase treatments, it may be necessary 35 to introduce a regulated amount of steam, which feature is included within the scope of the invention.

The choice of treating either in liquid or vapor phase will be determined by the results obtained 45 in any given case and it is not to be inferred that these two types of treatment are necessarily equivalent in their action upon any particular cracked distillate.

A special advantage in the present type of 50 treatment resides in the fact that mercaptans may be removed directly, in contrast to sweetening processes employing such reagents as sodium plumbite and sulfur, and sodium hypochlorite solutions, both of which convert mercaptans to disulfides which remain dissolved in the oil. In 55 the case of sodium plumbite, there is ordinarily an additional hazard in the use of sulfur to "break" the solution of mercaptides produced by the first step of the treatment. Experiments have shown that in many cases the tendency of sweetened cracked gasolines to become cloudy after exposure to light is due to dissolved sulfur or to sulfides or disulfides, since complete removal of these classes of sulfur compounds produces a gasoline which remains clear for a much greater period of time.

The following examples are illustrative of the results obtainable by the use of reagent solutions of the present character in treating cracked distillates and gasolines.

A cracked naphtha produced from a California gas oil charging stock was treated with about 1% to 2% by volume of an aqueous solution corresponding in composition to that of Solution No. 2 shown in the table given above. After separation

of the reaction products the naphtha was redistilled with steam and fractionated to produce a gasoline having the properties shown in column No. 2 of the following table. Column No. 1 shows the corresponding properties of the gasoline produced from the same naphtha when no treatment was used:

Properties of untreated and treated gasolines

	1	2	85
Gravity °A.P.I.	53.6	53.8	
Mg. of gum by copper dish	250	25	
Total sulfur, percent	0.35	0.15	
Doctor test	Positive.	Negative.	
Initial boiling point, °F.	96	100	90
Final boiling point, °F.	410	408	

As an example of results obtainable when treating in vapor phase, the following may be cited. The vaporous effluent from the secondary fractionator of a cracking plant operating upon a West Texas residuum may be passed upwardly countercurrent to a descending solution of a composition corresponding to Solution No. 3, using steam to prevent crystallization of the solutes. The temperature of the treater may be approximately 310° F. and the pressures about 50 pounds per square inch. A comparison of the gasoline recovered from this treatment and the gasoline producible from the vapors without chemical treatment is shown in the following table:

Comparison of untreated and treated gasolines

	1	2	110
Gravity °A.P.I.	54.2	54.5	
Mg. of gum by copper dish	275	30	
Total sulfur, percent	0.38	0.14	
Doctor test	Positive.	Negative.	
Initial boiling point, °F.	98	103	105
Final boiling point, °F.	412	409	115

The value of the process is evident from a consideration of the above data, but since many other examples could be introduced the scope of the invention is not to be limited to the figures shown. Correspondingly, the descriptive portion of the specification is not to act in an unduly limiting sense.

I claim as my invention:

1. A step in the process for the treatment of cracked hydrocarbon oil to reduce the sulphur content thereof and to refine the same, which comprises subjecting the said cracked hydrocarbon oil to the action of a solution containing a mercury salt and a copper salt.

2. A step in the process for the treatment of cracked hydrocarbon oil to refine the same and to substantially reduce the sulphur content thereof, which comprises subjecting the said cracked hydrocarbon oil to the action of an aqueous solution containing a mercury salt and a copper salt.

3. A step in a process for the treatment of cracked hydrocarbon oil to refine the same and to substantially reduce the sulphur content thereof, which comprises subjecting the said cracked hydrocarbon oil to the action of an aqueous solution containing mercuric chloride and a copper salt.

4. A step in the process for the treatment of cracked hydrocarbon oil to refine the same and to substantially reduce the sulphur content thereof, which comprises subjecting the said cracked hydrocarbon oil to the action of an aqueous solution containing mercuric chloride and cupric chloride.

JACQUE C. MORRELL. 150
